SELF-CONTAINED BATTERY OPERATED DENTAL APPLIANCE

John B. Fattaleh, 4845 E. Indian School Road,
Phoenix, Ariz. 85018

Filed July 26, 1974, Ser. No. 492,194

Term of patent 14 years

Int. Cl. D4—02; D24—02

U.S. Cl. D24—1 B

FIG. 1 is a perspective view of the front, top and right side of a self-contained battery operated dental appliance showing my new design;

FIG. 2 is a left end perspective view of the dental appliance;

FIG. 3 is a left end and bottom perspective view of the dental appliance;

FIG. 4 is a right end view of the dental appliance; and

FIG. 5 is a bottom view.

I claim:

The ornamental design for a self-contained battery operated dental appliance, as shown and described.
